UNITED STATES PATENT OFFICE

2,460,818

ELECTRIC SWITCH

Joseph F. Frese, Baltimore, Md., assignor to The
Monitor Controller Company, Baltimore, Md.,
a corporation of Maryland

Application April 27, 1944, Serial No. 533,010

7 Claims. (Cl. 200—48)

1

My invention relates broadly to electrical switches and more particularly to an automatically operated electric switch system.

One of the objects of my invention is to provide an arrangement of spring driven electric switch which may be instantaneously actuated by rendering the spring effective to drive the switch.

Another object of my invention is to provide a remotely controlled automatic switch that may be opened and/or closed under control of a spring motor which is conditioned from time to time by an electric motor.

Another object of my invention is to provide an arrangement of high potential switch which may be moved to open or closed position under control of a spring driven motor at uniform speed where the spring driven motor is wound from time to time under control of an electric motor.

Still another object of my invention is to provide a construction of spring governed switch having an electric motor winding device associated therewith and in which a multiplicity of coacting auxiliary contacts are controlled synchronously with the operation of the switch.

A still further object of my invention is to provide a construction of electric switch in which a pair of switch arms may be automatically moved in opposite directions simultaneously under control of a spring motor actuator for opening and/or closing electric circuits.

Still another object of my invention is to provide a construction of spring operated actuator for driving the arms of an electric switch system where the spring operator is wound from time to time as required by an electric motor.

A further object of my invention is to provide a construction of auxiliary contact system operated by cam devices controlled by the movement of the electric switch system of my invention.

Still another object of my invention is to provide a high potential switch system including insulators for mounting angularly movable arms having contactors thereon in combination with mechanism for moving the arms in clockwise and counter-clockwise directions for making and breaking connection with stationary contacts insulatedly mounted in alignment with the switch arms.

Still another object of my invention is to provide a construction of reversed drive mechanism for a pair of electric switches with means for simultaneously moving the electric switches in opposite directions with respect to each other for making or breaking coacting electrical connections.

2

Other and further objects of my invention reside in the construction and arrangement of parts of the automatic switch as set forth in the accompanying specification and shown in the accompanying drawings in which Figure 1 is a plan view of the automatic switch system and actuator therefor; Fig. 2 is a top plan view of the automatic switch system and drive therefor; Fig. 3 is a side view of the automatic switch system and actuator; Fig. 4 is a view illustrating the arrangement of auxiliary contacts in association with one of the switch arms and illustrating the automatic drive control mechanism in association therewith; Fig. 5 is a plan view showing one of the switch arms carried by the insulator; Fig. 6 is an end view of the hardware which supports the switch arm with respect to the insulator; Fig. 7 is a cross sectional view through the hardware and insulator showing the support of the switch arm thereby; Fig. 8 is a transverse sectional view taken on line 8—8 of Fig. 4 illustrating the stationary contact which is carried by an insulator mounted on the apparatus panel; Fig. 9 is a plan view showing the auxiliary contacts and the arrangement of cams for controlling the contacts synchronously with the movement of the switch arm; Fig. 10 is a longitudinal sectional view through the cam control mechanism for the auxiliary contacts; Fig. 11 is an end view of the switch actuator for effecting rapid operation of the automatic switch; Fig. 12 is a transverse sectional view through the case taken on line 12—12 of Fig. 17, the view being partially broken away; Fig. 13 is a fragmentary composite sectional and elevational view of the floating connection between the bell crank and brake actuating lever; Fig. 14 is a detailed view of the brake actuating arm; Fig. 15 is a detailed view of the brake applicator arm; Fig. 16 is an end view of the arm shown in Fig. 15; Fig. 17 is a transverse sectional view taken substantially on line 17—17 of Fig. 19; Fig. 18 is a transverse sectional view taken substantially on line 18—18 of Fig. 19; Fig. 19 is a view showing the relative arrangement of the power spring and the spring winding mechanism taken substantially on line 19—19 of Fig. 11; Fig. 20 is a plan view of one of the drums employed in driving the switch arms showing the adjustable members thereof; Fig. 21 is an end view of the drum shown in Fig. 20; Fig. 22 is a fragmentary sectional view illustrating how the driving band is adjustably held in place; Fig. 23 is an end view of the coacting drum which connects with the driving bands for driving the switch arms; Fig. 24 is a fragmentary sectional view

taken on line 24—24 of Fig. 23 showing the method of fastening the opposite ends of the bands that are fixedly secured on drum 34 and adjustably secured on drum 50; Fig. 25 is a view of one of the adjusting screw terminus members secured to the end of the driving band; Fig. 26 is a plan view of one of the actuating cams employed in the switch actuating mechanism; Fig. 27 is a side elevational view of the cam shown in Fig. 26 and Fig. 28 is a schematic view of the switch system of my invention illustrating one arrangement of circuit system to which the automatic switch may be applied.

Referring to the drawings in detail reference characters 1 and 2 designate the switch arms which are carried in fittings 3 and 4 respectively carried on the insulators 5 and 6. The manner of securing the arms to the insulators is shown more particularly in Figs. 5, 6 and 7 wherein it will be seen that the hardware 3 and 4 are recessed as indicated at 7 to fit over the metallic cap member 8 which is secured by a suitable coating of cement or metallic layer indicated at 9 to the end of the insulator. The cap 8 has a projection 10 thereon which is centrally recessed and screw-threaded at 11 to receive the screw-threaded member 12 which forms the connection means for the flexible cable 14 constituting the electrical connection for the switch arm. Set screws 13 extend through threaded apertures in the hardware 3 and 4 and engage the projecting end of the metallic cap at 10 for firmly securing the switch arm in position with respect to the insulator 5. The hardware fittings 3 and 4 contain arcuate shaped lipped portion 15 through which a set screw 16 may extend for locking the hexagonal head 17 of the screw-threaded terminal member 12 of the flexible cable 14 for insuring firm position of the switch arm with respect to the insulator 5. The switch arms carry at their ends spring contact members which I have illustrated at 18 and 19 shaped to present flat parallel faces to the coacting jaws of the fixed contacts and which are secured to opposite portions of the switch arm. The faces of contacts 18 and 19 are silvered to insure good conductivity under conditions of arcing when establishing connection with the coacting faces of the coacting switch jaws. The switch arm is slotted throughout a portion of its length as represented at 20 to impart sufficient resiliency to the contact members 18 and 19 and thus insure good electrical contact when the contact members 18 and 19 engage between the jaws 20 and 21 of the fixed contactor represented at 22. Conditions of vibration are thereby prevented from displacing or disturbing the contact so that the switch system is applicable in any place subject to vibration. The opposite jaws 20 and 21 have their interior faces coated with a silver lining 20a and 21a to increase conductivity. The means for securing hardware 22 constituting the stationary contact with respect to the insulator are identical with the means for securing the hardware 3 and 4 constituting the support for the movable contactor or switch arm in order to facilitate production and reduce manufacturing and maintenance costs. The number of replacement parts may thereby be maintained at a minimum. Electrical connection is established with the fixed contact in any suitable manner such as the method explained in connection with the movable contact or through a lug and screw arrangement designated generally at 23. Securing means 13a similar to the securing means 13 for the hardware

associated with the movable switch arm are employed for securing the stationary hardware with respect to insulator 6.

I have described the switch arm construction for one of the switches in detail and it will be understood that the other arm is constructed in a similar manner and that corresponding reference characters indicate similar parts. I have illustrated my invention applied to a two-pole 10 single throw switch, but it will be fully understood that the construction may be applied to a double throw system or multiple contact arrangement.

The insulators 5 and 6 are movable with respect to a panel represented at 24 which provides 15 mounting means for the automatic switch operating mechanism, the auxiliary contact system, the driving motor and the motor control mechanism.

Stationary contactor 22 carried by insulator 6 is mounted directly upon the panel by the socket base 25. Socket base 25 is suitably secured by flange bolts 26 to panel 24. The movable insulators 5 and 6 are each supported as illustrated in Figs. 9 and 10. Insulator 5 is secured in a socket member 27 which is secured in any suitable manner to the flange member 28 carried by the shaft 29. Shaft 29 is journaled in sleeve bearing 30. The sleeve bearing 30 is oilless and does not require lubrication. It is supported in housing 31 which forms part of the base casting 32 secured to the panel by through bolts represented at 33. The sleeve bearing 30 extends the full length of the housing 31 which terminates in a position forming an abutment for the hub portion 32 of the drum 34. Drum 34 has two peripheral grooves 35 and 36 within which the driving bands 37 and 38 operate. Drum 34 also carries stud bolts 39, 40 and 41 each of which include spacing sleeves 39a, 40a and 41a thereon. The spacing sleeves serve as supporters for the cam members represented at 42, 43 and 44. The end members of each of the stud bolts are formed from insulation material represented at 39b to insure against electrical breakdown between the metallic casting 45 or housing 32 and the stud bolt fastening screws indicated at 39c. Similar insulated end members are provided on the coacting stud bolts.

The drum shown at 34 coacts with a drum 50 which is associated with the movable shaft 6. Drum 50, however, is formed differently than drum 34 as represented more particularly in Figs. 19, 20 and 21 as provision is made for the tightening of the bands and the adjustment of contact arm 6 in order to insure proper alignment of the switch arms with respect to the stationary contacts. Drum 50 contains annular grooves 51 and 52 with lugs extending into the path thereof represented at 53 and 54 respectively around a chordal portion 55 of the drum. Each of the lugs are apertured to receive adjustably screw-threaded bolt members 56 shown more particularly in Fig. 24. The bolt members 56 are bifurcated at their ends and are attached to the bands shown at 37 and 38. The opposite ends of the bands 37 and 38 terminate under screw heads 57 and 58 engageable in the peripheral of drum 34 as illustrated in Figs. 22 and 23. It will be observed that the ends of the bands 37 and 38 are reinforced as represented, for example, at 37a to enable them to be secured under the securing screws such as 57 and 58 in drum 34 and allow precise control of effective length. The adjustment is made by tightening or loosening the adjusting nuts 56a on the coacting screw-threaded bolt member such as 56 in Fig. 21. Thus adjust-

ability may be effected on drum 50 while permanent connections are established on drum 34. The drum 34 is provided with screw-threaded openings into which fastening screws 59 may be inserted for securing bracket member 60 in position. Bracket member 60 forms a connecting means for the actuating link 61 leading to the cams 62 and 63 of the switch operating mechanism.

There are two of these cams one of which is shown at 62 and the other of which is shown at 63. Cams 62 and 63 are exact opposites of each other and have opposite actuating faces 62b and 63b. The link 61 is pivotally connected to the stud bolt 64 which is pivoted in cam 63 but passes loosely through cam 62. The two cams are mounted on shaft 65 which has two flat portions 66, one on each side thereof. One cam 62 is recessed at 68 as shown in Fig. 19 to receive washer member 68a and the head of the retaining screw 69 that extends therethrough and which connects to the tapped portion of shaft 65. The two cams 62 and 63 also have internal flat faces shown at 62a and 63a to engage upon the coacting flat faces of the projecting end of the shaft 65 thus keying or locking the cams 62 and 63 to rotate fast with the extension of shaft 65 shown at 67. Extension shaft 67 extends transversely of the casing 68 and is journaled therein at opposite ends represented at 69 and 70. The bearing 70 is supported in the base plate 71 carried on the upper section of casing 68 by spacer members indicated at 72 held in place by screws 72a.

The shaft 67 thus journaled has an enlarged section which is screw-threaded which is represented at 73. Below the screw-threaded section 73 are two flats represented at 74 on which there is mounted a cam 75 which turns with the shaft 67. A traveling nut 76 is arranged to move over the screw-threads 73 and traverses a path extending parallel with the shaft guided by two studs 77 and 78 which pass through coacting apertures in traveling nuts 76. On traveling nut 76 there is carried a projecting cam face 79 which is arranged to coact with face 80 of the cam 75 when the nut approaches its limit of travel on screw-threads 73. The studs 77 and 78 are carried by worm gear 81 as shown. The base portions of the mounting means for studs 77 and 78 are cut away at 77a and 78a to allow clearance for the cam 75. The worm gear 81 has a sleeve portion 83 rotatably mounted on shaft 67 within the spring case shown at 84. The spring case 84 houses flat spiral spring 85 which is secured at one end to the case 84 and at the opposite end to the sleeve 83. The bushing 87 of the spider gear wheel 132 is pinned to the shaft 67 as represented at 88. The spider gear wheel 132 forms one end of the spring case 84. The spring case 84 remains stationary while spring 85 is being wound.

The manner of winding the springs 85 will be more clearly understood by considering the arrangement of the driving motor 89 which is supported on panel 24. Motor 89 may be of any desired type for driving shaft 90 through suitable coupling 91 which connects to shaft 92 journaled in bearing 93 in the side wall of casing 68 terminating in pinion 94. Pinion 94 engages with the gear 95 which is carried by shaft 96. Shaft 96 is journaled in bearings 97 and 98 in opposite ends of the casing 68 and carries worm gear 99 thereon which engages with the worm wheel 81. Thus the driving motor 89 is enabled to rotate sleeve 83 which is connected to spiral

spring 85 for winding spiral spring 85 within housing 86. During this winding operation the traveling nut 76 moves away from the cam 75 on screw-thread 73 and at the limit of its travel engages pin 100 which acts upon arm 101. Arm 101 is pivoted on block 102 on the exterior of casing 68. An extension 103 on arm 101 is operated to engage operating member 103' of micro-switch 104. Micro-switch 104 is arranged in the motor circuit or in circuit with a relay that is arranged in the motor circuit and thus opens the power circuit to the motor when the spring 85 has been wound to a predetermined tension. The spring 85 is thus operative to control the operation of the automatic switch.

Mounted on the sub-base of the casing 68 I provide a solenoid 105 having an armature member 106 which is pivotally connected at 107 with arm 108. Arm 108 is pivoted at 109 on casing 68. The angular movement of arm 108 is restricted by bracket member 110. A counterweight 111 is carried by the movable arm 108 and is connected through spring 112 to the fixed stud 114 on casing 68 thus tending to maintain the arm in the full line position illustrated in Fig. 3. The arm 108 carries a movable bracket member 115. Bracket member 115 is bolted to bell crank 116 which is in turn pivoted at 117. The opposite end of the bell crank 116 shown at 118 is engaged beneath washer member 119 (Fig. 23) mounted on stud 120 projecting from casing 68. Arm 121 is also mounted on stud 120 and is free to move angularly about stud 120. Bell crank 116 is pivoted on stud 117 which is fastened in lever arm 121 so that when bell crank 116 moves it shifts arm 121 in a circular path and applies a brake band represented at 122 to the brake drum shown at 123. Brake band 122 is normally loose about drum 123 by action of spring 127 pressing against the end of lever arm 121 tending to slack off on the brake band 122. A spring 124 is arranged to maintain bell crank 116 against stud 125 which in turn maintains arm 121 in a position in which brake band 122 is unapplied. However, upon shifting of the bell crank 116 against the action of spring 124 when cam 62 operated by engagement with curved face 116a of bell crank 116 the bell crank moves back imparting motion to lever 121 applying tension to brake band 122 and establishing frictional contact with brake drum 123. The lever 121 and bell crank 116 are floating with respect to each other on pin 117 under tension by spring 124 and as bell crank 116 shifts it imparts motion to lever 121 which in turn increases tension on spring 127 through which stud 126 extends. Stud 126 in turn connects to the end of brake band 122 for thereby applying the friction brake in accordance with the angular displacement of lever 121. It will be observed that bell crank 116 has the end at 116a thereof so shaped that it is engaged by the curved face 62b of cam 62.

Without any current on the solenoid 105 bell crank 116 will be engaged with the lower cam 63, the power circuit being open through control switch 135. When current is applied from source 136 by closing switch 135 to the solenoid 105, the solenoid pulls in armature 106 rocking arm 108 (Fig. 3) about its pivot 109 and in turn moving bell crank 116. The movement of bell crank 116 shifts the abutment face 116a thereof from a position aligned with cam face 62b to a position aligned with cam face 63b. It will be observed that cam 63 is the exact counterpart of cam 62.

The engaging surface at 63b is curved in the manner similar to the curved surface 62b of cam 62. The curved surface 62b of cam 62 has the tendency of keeping bell crank 116 in engagement by drawing the bell crank inwardly rather than kicking the bell crank away which would be the situation if the cam face were flat or radial and not preformed as provided herein. Thus the spring 65 constituting the spring motor can drive the insulators 5 and 6 to certain predetermined limits determined by abutment of faces 62b or 63b with face 116a.

Flywheel 128 is carried by shaft 129 which is journaled at 130 and 131 in the casing 68 and frame 71 forming part of sub-base 71. The flywheel 128 insures a uniform speed of movement of the switch arms when the spring motor becomes effective to move the arms. The shaft 129 carries pinion 132 which meshes with the spider gear wheel 132 that forms part of the spring housing 84. Shaft 129 extends beyond case 62 and carries the brake drum 123 which is engaged by the brake band 122 operating as hereinbefore explained. The flywheel imparts sufficient inertia to the system to retard the spring from excessive speed of operation when the spring initially takes over control of the switch arms. In the operation of the automatic electric switch and contactor system of my invention control switch 135 is closed thereby energizing solenoid 105. Arm 108 is moved and imparts movement to bell crank 116 which shifts abutment face 116a from a position aligned with cam face 62b to a position in line with cam face 63b, thereby releasing shaft 67 which is driven by torsion spring 85. Link 61 connected to cam 62 drives drum 34 which simultaneously drives drum 50 in the reverse direction through the crossed bands 37 and 38. Thus insulators 5 are rotatably driven for driving switch arms 1 and 2 in coplanar relation. The switch arms 1 and 2 carrying the yieldably arranged contactors establish electrical connection with the contacts 22 mounted on the stand-off insulators 6. The reversed band arrangement 37-38 operates to drive the switch arms 1 and 2 in opposite directions in coplanar relation. Limited movement of the switch arms is controlled by the arrangement of abutment cams 62b and 63b. Constant driving torque is imparted to shaft 67 from torsion motor 85 which is wound by motor 89 during the energization thereof at the time solenoid 105 is energized. By the arrangement set forth herein quick operation of the switch arms is assured in opening and closing the electrical circuits controlled by the contactors.

While I have described my invention in one of its preferred embodiments, I realize that modifications may be made in the details and arrangement of the switch system and I desire that it be understood that my invention is not limited to the particular structures shown but may be changed as to detail within the scope of the appended claims.

What I claim as new and desire to secure by Letters Patent of the United States is as follows:

1. A high voltage switch comprising a supporting frame, stand-off insulators mounted on said frame, contact members mounted on said stand-off insulators, axially rotatable stand-off insulators mounted on said frame in spaced relation to the aforesaid stand-off insulators, movable switch arms mounted on said last mentioned stand-off insulators, said switch arms carrying contactors coacting with said contact members,

and means for rotating said last mentioned stand-off insulators and said switch arms in opposite angular directions in coplanar relation through approximately 90° to open and close the circuit through the contactors on said switch arms and said contact members.

2. A high voltage switch comprising a supporting frame, stand-off insulators mounted on said frame, contact members mounted on said stand-off insulators, rotatably mounted supports of insulation material extending from said frame adjacent said stand-off insulators, switch arms carried by said supports, contactors carried by said switch arms, and means for driving said switch arms in opposite angular directions in coplanar relation into and out of contacting relation with said contact members.

3. A high voltage switch comprising a supporting frame, stand-off insulators mounted on said frame, contact members mounted on said stand-off insulators, rotatably mounted rod-like insulators projecting from said frame in spacial relation to said stand-off insulators, switch arms carried by said rod-like insulators, contactors mounted on said switch arms, and means for driving said switch arms in opposite angular directions in coplanar relation for opening and closing circuits through the contactors on said switch arms and said contact members.

30. 4. A high voltage switch comprising a supporting frame, stand-off insulators mounted on said frame, contact members mounted on said stand-off insulators, axially rotatable stand-off insulators mounted on said frame in spacial relation to the aforesaid stand-off insulators, angularly movable switch arms carried by said last mentioned stand-off insulators, contactors carried by said switch arms and coacting with said contact members, means for simultaneously shifting said switch arms in opposite angular directions in coplanar relation for opening and closing electrical circuits through the contactors on said switch arms and said contact members and means for adjusting the angular travel of one of said switch arms with respect to the angular travel of a coacting switch arm.

5. A high voltage switch comprising a supporting frame, stand-off insulators mounted on said frame, contact members mounted on said stand-off insulators, axially rotatable stand-off insulators mounted on said frame in spacial relation to the aforesaid stand-off insulators, angularly movable switch arms carried by said last mentioned stand-off insulators, yieldable contactors carried by said switch arms and coacting with said contact members, means for simultaneously shifting said switch arms in opposite angular directions in coplanar relation for opening and closing electrical circuits through the contactors on said switch arms and said contact members, actuating drums connected with each of said switch arms, members interconnecting the peripheries of said drums, means for imparting angular movement to said drums and means for adjusting the effective lengths of said connecting members for individually adjusting the angular throw of said switch arms with respect to said contact members.

6. A high voltage switch comprising a supporting frame, stand-off insulators projecting normal from said frame, contact members mounted on said stand-off insulators, rotatably mounted rod-like insulators projecting normal from said frame in spacial relation to said stand-off insulators, switch arms carried by said rod-like insulators

yieldable contactors carried by said switch arms and movable into and out of contacting relation with said contact members, drums connected with each of said rotatably mounted rod-like insulators, said drums each having a pair of grooves on the peripheries thereof, connecting means extending around said grooves and reversed upon themselves for imparting opposite simultaneous angular movement to said drums and means associated with one of said drums for adjusting the effective length of said members for correspondingly controlling the angular throw of said switch arms.

7. A high voltage switch comprising a supporting frame, stand-off insulators mounted on said frame, contact members mounted on said stand-off insulators, axially rotatable rod-like insulators projecting from said frame in spacial relation to said stand-off insulators, switch arms having yieldable contactors thereon carried by said rod-like insulators and movable in coplanar relation into and out of contacting relation with said contact members, drums connected with each of said rotatable rod-like insulators, said drums each having multiple peripheral grooves thereon, connecting members reversed upon themselves and extending around the peripheral grooves of each of said drums, adjustable connecting means between the ends of said members and one of

5 said drums for adjusting the effective lengths of said members and correspondingly adjusting the angular throw of said switch arms, and means for imparting angular movement to the other of said drums whereby said first mentioned drum is driven through said connecting members for simultaneously controlling the movement of said switch arms with respect to said contact members.
